UNITED STATES PATENT OFFICE

VIRGIL F. ESPENSCHIED, OF HARTVILLE, OHIO, ASSIGNOR, BY MESNE ASSIGNMENTS, TO THE SCHUMACHER CORPORATION, OF HARTVILLE, OHIO, A CORPORATION OF OHIO.

ADJUSTABLE VENTILATOR

Application filed March 28, 1928. Serial No. 265,395.

This invention relates to ventilators of the louver type, which comprise metal sheets with louvers stamped therein. Adjustable ventilators of this type have been made for some time but they have been expensive for, so far as known, the adjustable features have been obtained by the addition of wings or extensions upon the ends of a louver metal sheet.

The invention herein described affords a new combination of frame members comprising or containing the metal sheets with sliding connections between the frame members, so that the devices are cheaply, easily and economically manufactured and operate satisfactorily at all times. The ventilator shown herein can be made much cheaper than former types of adjustable metal louver ventilators, and the advantages will be appreciated by those familiar with the prior ventilator of this form.

The preferred form of the invention is shown in the drawing, and will be described in detail, but it will be understood that changes and modifications may be made therein and that the invention is not limited to the details of construction except as set forth in the attached claim or as limited by the prior art.

In the drawing,
30 Figure 1 is a side elevation of a complete adjustable louver ventilator unit;

Figure 2 is a cross section on the line 2—2 of Figure 1; and

Figure 3 is a section at right angles to Figure 2 at the ends of the parts of the units.

Each ventilator comprises two units or sections 1 and 2 which are substantially identical in construction, except that they are oppositely placed. Each unit constitutes a frame member and consists of parallel rails 3 at the top and bottom and of a vertical or cross stile 4 at the end serving to unite the horizontal rails. The unit or section 1 is provided with dovetailed grooves 5 on the upper and lower rails and in these grooves are slideable short blocks 6 which are attached to and project from the upper and lower rails of the section 2. Similar blocks are secured to the rails of the section 2 and are slidably received in similar grooves on the section 1. The

blocks afford the sliding interlocking connection for the two sections of the ventilator, and separation of the sections is prevented by contact of these stops when the ventilator is opened to its greater extent. The rails 3 and the stiles 4 may be made of wood for lightness and economy of manufacture although the invention is not necessarily limited to wooden frame members. It will be observed that the sliding connection between the frame members is such as to space the metal sheets a sufficient distance apart to permit of longitudinal adjustability of the ventilator without interference between the louvers.

The inner edges of the rails and stiles, that is the surfaces surrounding the opening in each section, are provided with narrow grooves 8 and in these grooves are located the sheet metal plates 10 which are provided with the louver formations 12, stamped up from the metal. The size and arrangement of the louvers may be varied, as dictated by the requirements. Any suitable means may be employed to retain the plate 10 in position, a single nail 14 through the vertical stile being sufficient. It will be observed that the louvers are shown arranged in groups, the louvers of each group being spaced from the louvers of the adjacent group by an intermediate strip extending transversely of the individual louvers, the louvers being spaced, preferably, at a distance less than the length of the louvers. The result of this construction is to insure that, at any position of horizontal adjustment, the louvers in one of the sheets are always opposed by louvers in the other or overlapping sheet, whereby direct passage of air is always secured through the metal sheets. Exact horizontal alignment of the individual louvers is not essential so long as the groups of louvers are placed oppositely to one another.

The free edges of the sheets remote from the stiles may be ribbed or corrugated as at 15 for strengthening purposes and the edges may be bent inwardly as at 16 to close the spaces between the sheets and also to serve as stops, either in conjunction with or as a substitute for the blocks 6.

It will be noted that a very simple, effec-

tive and economical adjustable louver ventilator has been provided and that in operation it will always be readily adjustable. In addition, the sliding members of the ventilator cannot sag or warp as is the case with many adjustable, metal ventilators of this type.

What is claimed is:

- A horizontally adjustable ventilator comprising two frame members, adjustable sliding connections between the frame members, the frame members comprising overlapping metal sheets and louvers stamped in said sheets, an intermediate strip extending transversely of said louvers and spacing the louvers on each side thereof, the louver openings in the metal sheets being oppositely disposed, the adjustable sliding connections spacing the sheets at a sufficient distance to permit free adjustment of the frame members without interference between the louvers, the inner end of each sheet being bent to form a stop cooperating to limit the movement of the members, one of said stops being of a greater depth than the other so as to extend close to the surface of the other sheet.
